SANDING AND BUFFING TOOL

Filed Jan. 5, 1949

UNITED STATES PATENT OFFICE

2,577,498

SANDING AND BUFFING TOOL

Earl C. Applegate, Chicago, Ill.

Application January 5, 1949, Serial No. 69,355

9 Claims. (Cl. 51—187)

1

My invention relates to a sanding and buffing tool and has for its primary object the provision of a holding tool to which abrasive strips such as sandpaper, emery cloth, steel wool, etc. can be easily and quickly applied and removed therefrom and also providing a tool to which buffing or waxing pads can be attached in much the same manner for use in hand polishing various kinds and types of surfaces.

Another and further object of my invention is the provision of a tool to which abrasive strips can readily be attached and detached and which enables the operator to easily and quickly use these strips for abrasive purposes with the contours of the tool being such that entrance can be made into various types and kinds of openings, grooves and the like so that the tool may be used for polishing and abrading various contoured surfaces.

Another and further object of my invention is the provision of a sanding and abrading tool by means of which abrading strips can easily and quickly be attached and which during the process of attachment are drawn tautly around the base of the tool and securely held in position after being placed in proper position around the base of the tool, so that the tool can always be quickly and easily used for either abrasive or polishing action as may be desired.

Another and further object of my invention is the provision of a tool in which various thicknesses of abrasive material may be applied thereto and such material can be held in proper relationship on the base of the tool for use either as an abrasive or a polishing material. For instance, the dimension of the tool is such that the ordinary rectangular sheet of sandpaper or emery cloth can be folded in four or more layers and placed in position on the tool and as one surface becomes worn the material can be refolded in such manner that the unused portion can be placed in position for use in abrading and this process repeated until all the surfaces of the strips can be used. When this strip is folded the thickness of the material is, of course, materially increased and the tool is so constructed as to accommodate the holding of strips of material of varying thicknesses.

These and other objects of my invention will be more fully and better understood by reference to the accompanying sheet of drawings and in which:

Figure 1 is a top elevational view of my improved tool;

Figure 2 is a side elevational view of the tool shown in Figure 1;

2

Figure 3 is a longitudinal, sectional view on lines 3—3 of Figure 1; and

Figure 4 is a transverse, sectional view on lines 4—4 of Figure 2.

Referring now specifically to the drawings and in which like reference characters refer to like parts throughout, I provide a body member 10 comprising a hand hold portion 11 and a base portion 12, the said base portion being somewhat longer than the hand hold portion 11 and having a pointed end 13 at the forward end thereof and a vertical face 14 with an angular face 15 merging into the face 14 at the rear end, providing narrow flat portions for abrading or polishing into narrow grooves or the like.

The upper side of the base portion 12 has a step portion 16 at the rear end thereof adjacent which a recess 17 is provided, while at the forward end a similar step portion 18 is provided with a recess 19 provided between the hand hold portion 11 and the base 12 for purposes hereinafter described. The hand hold portion has an elongated finger recess 20 at one side thereof and a thumb recess 21 at the opposite side and near the forward end by means of which the operator spans the top of the hand hold portion and grips the hand hold 11 with his fingers in the recess 20 and his thumb in the recess 21 for easy and convenient gripping purposes. The upper surface of the hand hold portion is flat while the end portions 22 and 23 are rounded in contour in order that the hand hold portion 11 will more accurately fit the hand of the operator, as well as to secure a more effective working of the holding parts, which are hereinafter described.

Ribs 24, 24 are provided on diagonally opposite sides of the hand hold portion 11, which enable the operator to engage the hand hold portion 11 and protects the hand of the operator from abrasions due to the edges of the holding member hereinafter described. A highly tempered steel spring holding member 25 is provided which is secured to the hand hold portion 11 of the member by means of screws 26, 26 which are fitted into internally threaded nipples 27, 27 in the hand hold portion 11 of the base member 10, the base member 10 being made preferably of a plastic material molded to form or may be made of wood or any other similar or like material which can easily be worked or molded to the form as shown. The spring clip 25 has curved portions 28, 29 at each of its ends which terminate in lips 30 and 31 which extend outwardly from the curved surfaces 28 and 29 and are substantially parallel to the step surfaces 16 and 18 of the base portion 12 when in raised position,

but slightly canted as shown in Figure 3 when in closed position.

Transverse grooves 32 and 33 are provided adjacent the ends of the hand hold portion 11, these recesses providing shoulder portions 34, 34 with jack levers 36 and 37 being provided, which are rectangular in cross-section and are seated in the grooves 32 and 33 respectively and have inner end portions 38 and 39 angularly disposed thereon which normally fit into slots 40, 40 provided in the top of the hand hold portion 11 when the jack levers are in horizontal position. The jack levers 36 and 37 have finger pieces 41 and 42 on the outer ends thereof which project to the side of the hand hold portion 11 on opposite sides of the hand hold portion 11 with cut-outs 43 and 44 in the spring holding member 25 being provided to enable the operator to more easily engage the finger pieces 36 and 37 so as to manipulate the jack levers 36 and 37 and will be hereinafter described.

The jack levers 36 and 37 can be rotated only through an arc of 90° with the inside edges of the finger pieces 41 and 42 near the ends extending under the edge of the cover plate 25 particularly shown in Figure 1, so that these finger pieces cannot be rotated beyond substantially a horizontal position. The angular ends 38 and 39 of the jack levers 36 and 37 are normally fitted into the slots 40 and 41 formed in the hand hold portion 11, so that when these jack levers are in their normal horizontal position they will not drop out of place in the hand hold, nor can they be removed therefrom.

The jack levers 36 and 37 are rectangular in cross-section and when turned to vertical position lift the cover 25 so that its ends are in open position as shown at the right side of Figure 3. When turned into horizontal position their long diameter is parallel with the top of the block as shown in the left side of Figure 3, and they exert no pressure on the spring member 25, which moves to closed position because of its resiliency as shown at the front end of the tool in Figure 3 of the drawings. A cushion 45 is placed over the face of the base portion 12 of the tool and a strip of abrasive 46 is shown, which is in position around the ends of the base portion 12 and clamped by the end 31 of the spring holding member 25 at the forward end, but open at the rear end, as shown in Figure 3 of the drawings. The curved ends 22 and 23 of the hand hold portion conform to the curved ends of the holding member 25.

From the foregoing description it is believed that the operation of this device can be easily and quickly understood. When it is desired to place a strip of abrading or polishing material on the base 12 of the tool one of the jack levers is turned to vertical position, as shown in Figure 3, which frees the end of the spring member 25 under which the particular jack lever is mounted from the top surface of the stepped portions 17 or 18 and the abrasive material 46 is placed around the end of the base portion with its end under the raised free end of the spring holding member 25. In rotating the jack levers 36 and 37 to vertical position, they are supported by the edges in the channels 32 and 33 and rest against the shoulders 34, 34 and at the same time the sides of the angularly turned end portions 38 and 39 of the jack levers 36 and 37 engage against the underside of the cover 25 thereby preventing the over rotation of the jack levers 36 and 37, but holding the ends of the spring member 25 in

open position so that whatever material may be used such as an abrasive or polishing material can be placed in position around the base 12 of the holding member. If this material is longer than ordinarily required, the ends are fitted into the recesses 17 or 19 at the end of the hand hold 11 and upon the material being fitted around the base at one end the jack lever at that particular end is released and the material is clamped in position on the base member 12. The material is then drawn tautly around the opposite end of the base member 12 and inserted under the open end of the spring member 25 and the jack lever turned so as to release the spring holding member 25 into clamping position so that the ends of this member are fitted down over the ends of the abrasive 46 and the tool is ready for operation. Should it be necessary to replace or renew this material the reverse operation can be performed, providing a tool in which abrasive material or polishing material can be easily and quickly substituted by the operator for various kinds and classes of work.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

What is claimed is:

1. An abrasive or holding tool comprising in combination a body member having a hand hold portion and base portion of greater length than the hand hold portion whereby shelf portions are formed on the top of the said base portion, a spring clamping member secured to the body portion intermediate its ends and adapted to engage against the shelf portion of the base member and jack levers on said body member whereby the spring member may be raised at each of its ends and held in raised position the said body member having recesses therein for the reception of the said jack levers.

2. An abrasive or holding tool comprising in combination a body member having a hand hold portion and base portion of greater length than the hand hold portion whereby shelf portions are formed on the top of the said base portion, a spring clamping member secured to the body portion intermediate its ends and adapted to engage against the shelf portion of the base member and jack levers on said body member whereby the spring member may be raised at each of its ends and held in raised position the said body member having recesses therein for the reception of the said jack levers and having shoulder portions adjacent the recesses whereby the rotation of the jack levers is limited.

3. An abrasive or holding tool comprising in combination a body member having a hand hold portion and base portion of greater length than the hand hold portion whereby shelf portions are formed on the top of the said base portion, a spring clamping member secured to the body portion intermediate its ends and adapted to engage against the shelf portion of the base member and jack levers having angularly disposed end portions on said body member whereby the spring member may be raised at each of its ends and held in raised position the said body member having recesses therein for the reception of the said jack levers and having recesses therein for the

reception of the angularly turned end portions of the said jack levers.

4. An abrasive or holding tool comprising in combination a body member having a hand hold portion and base portion of greater length than the hand hold portion whereby shelf portions are formed on the top of the said base portion, a spring clamping member secured to the body portion intermediate its ends and adapted to engage against the shelf portion of the base member and jack levers having angularly disposed end portions on said body member whereby the spring member may be raised at each of its ends and held in raised position the said body member having recesses therein for the reception of the said jack levers and having recesses therein for the reception of the angularly turned end portions of the said jack levers, the angularly turned end portions engaging the spring clip member whereby the said jack levers are restricted in their rotative movement.

5. An abrasive or holding tool comprising in combination a body member having a hand hold portion and base portion of greater length than the hand hold portion whereby shelf portions are formed on the top of the said base portion, a spring clamping member secured to the body portion intermediate its ends and adapted to engage against the shelf portion of the base member and jack levers having finger pieces thereon one edge of which engages the spring clamping member when the jack levers are in horizontal position, on said body member whereby the spring member may be raised at each of its ends and held in raised position the said body member having recesses therein for the reception of the said jack levers.

6. An abrasive or holding tool comprising in combination a body member having a hand hold portion and base portion of greater length than the hand hold portion whereby shelf portions are formed on the top of the said base portion, a spring clamping member secured to the body portion intermediate its ends and adapted to engage against the shelf portion of the base member and jack levers on said body member whereby the spring member may be raised at each of its ends and held in raised position the said body member having recesses therein for the reception of the said jack levers, the said jack levers being limited in rotation in each direction.

7. An abrading tool comprising in combination an elongated integrally formed body member having a support for abrading material and a hand hold portion for the operator of the tool, the said hand hold portion having notches at each of its ends in the upper side thereof, the support for the abrading material being of greater length than the hand hold portion whereby stepped portions are provided at each of its ends, a leaf spring extending longitudinally of the said tool having free end portions in normal engagement with the said stepped portions, fastening members secured to the said tool for the leaf spring and rotatably mounted independently movable levers mounted in said notches in the hand hold portion of the tool, each said lever having a greater width than thickness and normally lying in a plane parallel to the longitudinal plane of the tool and when turned to vertical position serving to hold one end of the leaf spring free of one of said stepped portions of the tool.

8. An abrading tool comprising in combination an elongated integrally formed body member having a support for abrading material and a hand hold portion for the operator of the tool, the said hand hold portion having notches at each of its ends in the upper side thereof, the support for the abrading material being of greater length than the hand hold portion whereby stepped portions are provided at each end of the tool, a leaf spring extending longitudinally of the said tool having free end portions in normal engagement with the said stepped portions, fastening members secured to the said tool for the leaf spring and a plurality of levers mounted in the said notches fulcrumed on the hand hold portion of the said tool having finger pieces at one of their ends, said levers being adapted to engage the ends of the said spring whereby when moved to operative position the ends of the said spring are raised out of engagement with the support for the abrading material and held in such disengaged position.
9. An abrading tool comprising in combination an elongated integrally formed body member having a support for abrading material and a hand hold portion for the operator of the tool, the said hand hold portion having notches at each of its ends in the upper side thereof, the support for the abrading material being of greater length than the hand hold portion whereby stepped portions are provided at each of its ends, a leaf spring extending longitudinally of the said tool having free end portions in normal engagement with the said stepped portions, fastening members for the leaf spring secured to the said tool and rotatably mounted independently movable levers mounted in said notches in the hand hold portion of the tool, the said levers having a greater width than thickness and normally lying in a plane parallel to the longitudinal plane of the tool and when turned to vertical position serving to hold the ends of the leaf spring free of the said stepped portions of the tool, the said levers having end portions thereon on their ends opposite the finger pieces for engagement with the said leaf spring whereby the said levers are prevented from turning beyond a position slightly past dead center when turned to raise the ends of the said leaf spring.
